DESIGN.

—o—

F. R. GILLINDER.

CROWN GLOBE.

16,746.

Patented June 22, 1886.

UNITED STATES PATENT OFFICE.

FREDERICK R. GILLINDER, OF PHILADELPHIA, PENNSYLVANIA.

DESIGN FOR A CROWN-GLOBE.

SPECIFICATION forming part of Design No. 16,746, dated June 22, 1886.

Application filed November 25, 1885. Serial No. 183,997. Term of patent 7 years.

To all whom it may concern:

Be it known that I, FREDERICK R. GILLINDER, a citizen of the United States, residing in the city and county of Philadelphia, State of Pennsylvania, have invented and produced a new and original Design for Crown-Globes, of which the following is a specification, reference being had to the accompanying photograph, forming part thereof.

10 The leading feature of my design is the representation on the neck and rim of a globe of an ornamentation continuous of that on the body thereof.

15 A represents the body of a globe, B the neck, and C the rim at the top of the globe, said neck being between the rim and body. The

entire body A is ornamented by figures having a raised appearance thereon, and the entire neck and a portion of the rim are similarly ornamented, the ornamentation of the body, 20 neck, and rim being continuous, the plain portion of the rim being near its edge.

I claim—

A design for a crown-globe having a globular body, a rim at top, and a neck between the 25 same, and a continuous raised ornamentation on said body, neck, and rim, as shown and described.

FREDERICK R. GILLINDER.
